GAME SCORING DEVICE WITH SCORE INDICATING LIGHTS

George E. Kochem, Schenectady, N. Y.

Application July 22, 1946, Serial No. 685,305

2 Claims. (Cl. 177—337)

1

My invention relates to competitive games, and particularly to scoring devices for such games. It is a primary object of my invention to provide a new and improved game scoring device which indicates visually both the present and previous scores of the competitors or team of competitors.

In certain types of competitive games, such as for example the game of shuffle board, the rules of competition require that a record be kept not only of the scoring at each particular moment, but also of the scores of the competitors at the time of the previous scoring opportunity. Accordingly, it is a further object of my invention to provide a new and improved game scoring device which indicates both the score of the individual competitors at the present moment of competition and their scores at the end of the previous scoring opportunity.

It is a still further object of my invention to provide a new and improved construction of a score board which gives a clearly defined visual indication of the scores of the competing parties.

It is still another object of my invention to provide a new and improved game scoring device which is easily constructed and easily operated.

The novel features which I believe to be characteristic of my invention are set forth with particularity in the appended claims. My invention itself, however, both as to its organization and method of operation together with further objects and advantages thereof, may best be understood by reference to the following description taken in connection with the accompanying drawing in which Fig. 1 is a front elevation view of a game scoring device suitably embodying my invention; Fig. 2 shows the device of Fig. 1 with the front cover removed; Fig. 3 is a vertical sectional view of the device of Fig. 1 taken along the line 3—3; and Fig. 4 is an enlarged sectional view of a plug and contact used in my game scoring device.

Referring to Figs. 1-3 jointly, I have there illustrated my game scoring device as comprising an enclosing member or cabinet having a front panel 1 and a hollow rectangular body portion 2. The front portion may consist of a pressed fiber board or any other suitable material which contains two parallel sets 3, 4 of vertically aligned apertures. Positioned above the sets 3, 4 of apertures is a translucent panel 5 which may consist, for example, of glass having a frosted surface. Overlying the apertures and supported on the translucent member 5 are numerals or indicia 6, successive ones of the indicia 6 in vertical alignment corresponding to successive possible

10 scores of the game which is being scored. Thus, in the case of shuffle board for example, 21 apertures are provided in each of the sets 3, 4 and the indicia 6 begin with the numeral 1 positioned above the uppermost of the apertures and end with the numeral 21 above the lowermost aperture. The indicia 6 may comprise any suitable lettering which is opaque to light, such as for example gold leaf letters which are attached to the surface of the translucent panel 5.

15 Near the upper end of the front panel 1 are located a pair of apertures 7, 8 which are likewise covered with a translucent member and carry identifying characters 9, 10 which represent the contestants or competitors in the game. Vertically aligned on opposite sides of the member 5 are two sets 11, 12 of normally open electrical contacts or jacks into which a plug contact may be inserted. Positioned respectively beside each 20 of the sets of contacts 11, 12 are sets 13, 14 of small circular indicators which bear indicia corresponding to the indicia 6. Thus, for example, for the game being described, the indicia on the indicators 13, 14 are numerals 1-21. Positioned above the sets 11, 12 of contacts are two contacts or jacks 15, 16 of the normally closed type and which are operated by insertion of a plug to open the contacts therein. Referring now particularly to Figs. 2 and 3, there is contained within the hollow rectangular member 2 a body member 17 having recesses 18 therein which underlie the sets of apertures 3, 4 in the front panel 1. Positioned within each of the recesses 18 is a source of light 19 which may be a small electric lamp. The lamps 19 may be of the bayonet-base type and are supported in a receptacle 20 adapted to receive this type of lamp. Each of the receptacles 20 has one electrical contact which is connected by means of a short conductor 21 to a vertically arranged supply conductor 22. The receptacle has its other contact connected by means of a conductor 23 to one terminal of the one of the sets of jacks 11, 12 which corresponds to the particular lamp in question. Thus, the lamp 19 under the numeral 1 in the set 3 of lamps is connected to the uppermost jack of the set 11 of contacts or jacks. This is the contact which is positioned beside the indicator bearing the numeral 1. Similarly, any other lamp in the set of lamps 3, for example the lamp 2, has its left-hand terminal connected by means of a conductor 23 to one of the contacts of the jack in the set 11 opposite the numeral 2.

25 The jacks of the sets 11, 12 are best seen in Figs. 3 and 4 and consist of an upper contact 24

which is in direct contact with the outer flange 25 of an L-shaped metallic member or plate 26. The member 26 may be directly supported from the body member 17 by means of screws 27. The upper contact 24 comprises a head portion 28 (Fig. 4) which lies against the outer surface of the flange 25 and a tubular body portion 29 which extends through an aperture provided in the flange 25. The body portion 29 extends to the opposite side of the flange 25 and is surrounded by a tubular insulator 30 which supports a rearwardly extending contact 31. The jack assembly is held in position on the flange 25 by means of an insulator 32 and a nut 33. Preferably, the contact 31 is resilient and bent downwardly so that it extends in back of the body portion 29 and may be engaged by a metallic plug 41 which is inserted into the contact. The conductor 23 of the respective lamps 19 is directly connected to the contact 31. The metal plate 26 is connected by means of a conductor 34 to one terminal of the secondary winding of a transformer 35 shown in Fig. 2. The opposite terminal of the secondary winding of the transformer 35 is directly connected to the vertical conductor 22. The primary winding of transformer 35 is adapted to be energized from any suitable source of alternating voltage by means of the conductors 36. Preferably, the transformation ratio of transformer 35 is such that voltage provided by the secondary winding is of the order of 6 volts so that conventional low voltage lamps may be employed as the lamps 19.

The normally closed contacts 15, 16, which are connected in series with the lights 37, 38 underlying, respectively, the identifying characters 9, 10, are similar in construction to the sets of contacts 11, 12 with the exception that a flexible member 39 shown in Fig. 3 is connected to the body member 29 and normally engages the conductor 31. The flexible member 39, therefore, may be engaged by the inner end 40 of the plug 41 to open the contact 15 or 16 in which it is inserted and to deenergize the associate one of the lamps 37, 38. In Fig. 3 the plug 41 is shown only partially inserted into one of the contacts 15, 16. The conductor 31 of the normally closed contacts 15, 16 is connected to one of the terminals of the lamps 37, 38 by means of a conductor 42. The opposite terminals of the lamps 37, 38 are connected by means of conductors 43 to the lead 22 and one side of the secondary winding of transformer 35. The circuit of the lamps 37, 38 is completed through the conductive connection of the upper contact 24 of the normally closed contacts 15, 16 with one of the metal plates 26. The two metal plates are conductively connected at their lower ends by means of the conductor 44.

In the use of my game scoring device to indicate the score of a game of shuffle board, for example, when the plugs 41 are withdrawn from the jacks 15, 16, the circuits of the lamps 37, 38 are completed and the indicia 9, 10 are illuminated to indicate which of the sets of lights 37, 38 registers the scores of the competitors A and B. After the competitor A completes his first round of scoring, which may amount to, for example, 2 points, the plug 41 is inserted in the one of the set of contacts 11 opposite the indicator 2. This completes the circuit to the lamp 19 which is behind the indicia 2 in the left-hand set 3 of apertures and indicia. Also, the contestant B inserts a plug in the one of the jacks 12 which corresponds to his score at the end of the round in which he first scores. If the competitor A in the round in which he scores a second time acquires

4 additional points, he finds, upon glancing at the score board, that his previous score was 2 and that his present score therefore is 6. He then inserts a second plug in the one of the set of contacts 11 opposite the indicator 6. This completes the circuit of the lamp behind the indicia 6 in the set 3 of such indicia. At this time, therefore, both the indicia 2 and 6 are illuminated, indicating both the present and previous score of the contestant A. In this way, there is indicated in the set of indicia 3 not only his score at the present time, but likewise the score at the end of his previous scoring opportunity. Likewise, the contestant B uses two plugs 41 to identify both his present score and his previous score. At the end of the round in which he scores the third time, the contestant A removes the plug from the jack opposite the indicator 2 and places it in the one of the contacts 11 opposite the score at the end of his third scoring effort. Thus, if his score at that time is 9 points, he inserts the plug in the jack 11 opposite the indicator 9. At the completion of the game, both contestants withdraw all plugs and insert one of the plugs into the jacks 15, 16 to extinguish the contestant identifying lamps 37, 38.

One important advantage of my improved construction is that it provides a clearly defined indication of the scores which is visible at a large distance from the scoring device, so that the numerals may be seen distinctly by both contestants and spectators in daylight, as well as at nighttime. In this respect, each of the lamps 19 is located within an enclosure, the only outlet of which is through the translucent member 5. Thus, referring to Fig. 3, for example, it is seen that each of the lamps 19 is wholly surrounded by the walls of the body member 17. Since the body member 17 extends up to and fits closely against the panel 4, the sole outlet for light from the lamps 19 is through the portion of translucent member 5 overlying the particular recess 18. At the same time, the light rays do not illuminate any of the adjacent portions of the member 5, so that only one of the indicia is illuminated by any one light 19. In this respect, I have found that a thin paper covering, for example a tissue paper covering 45, on the surface of the member 5 facing the light assists in bringing into clear relief the indicia 6 on the outer surface of the translucent panel.

Another important advantage of my improved game scoring device is that it permits an accurate indication not only of present scores of the competitors, but also the scores at the end of their previous scoring opportunities.

While I have shown a particular embodiment of my invention, it will of course be understood that I do not wish to be limited thereto since many modifications may be made and I contemplate by the appended claims to cover all such modifications as fall within the true spirit and scope of my invention.

What I claim as new and desire to secure by Letters Patent of the United States is:

1. A game scoring device comprising a body member having two adjacent parallel rows of recesses therein, a respective light source positioned in each of said recesses, an opaque cover enclosing said body member, said cover having translucent portions closing the entrances to said recesses, said portions forming the sole outlet for light from said sources, a pair of metallic members arranged respectively on opposite sides of said body member, two parallel rows of contacts insulating supported on said metallic members

and arranged on opposite sides of said recesses, the contacts in each row being connected with the lights in the adjacent row of recesses, each of said contacts being connected in series with the correspondingly positioned light source, a source of electrical energy connected in series with said lights and said metallic members, indicia corresponding to successive scores of a game to be scored supported on adjacent ones of said portions, corresponding indicia positioned adjacent corresponding ones of said contacts, said metallic members having apertures aligned with said contacts, and a movable contact making member for connecting a desired one of said contacts with its associated metallic member to energize the corresponding light source and illuminate the corresponding indicium associated with said light source.

2. A game scoring device comprising a body member having two adjacent parallel rows of recesses therein, a respective light source positioned in each of said recesses, an opaque cover enclosing said body member, said cover having translucent portions closing the entrances to said recesses, said portions forming the sole outlet for light from said sources, a pair of metallic members arranged respectively on opposite sides of said body member, two parallel rows of contacts insulatingly supported on said metallic members and arranged on opposite sides of said recesses, the contacts in each row being connected with the lights in the adjacent row of recesses, each of said contacts being connected in series with

the correspondingly positioned light source, a source of electrical energy connected in series with said lights and said metallic members, indicia corresponding to successive scores of a game to be scored supported on adjacent ones of said portions, corresponding indicia positioned adjacent corresponding ones of said contacts, said metallic members having apertures aligned with said contacts, a movable contact making member for connecting a desired one of said contacts with its associated metallic member to energize the corresponding light source and illuminate the corresponding indicium associated with said light source, a pair of identifying lights positioned respectively adjacent a respective one of said rows of recesses, and a normally closed contact connected between each of said identifying lights and said source, whereby when said device is not in use said contact making members may be stored in said normally closed contacts to extinguish said identifying lights.
